VALVE-REGULATING MECHANISM.

1,041,273

Specification of Letters Patent.

Patented Oct. 15, 1912.

Application filed October 18, 1906. Serial No. 339,462.

To all whom it may concern:

Be it known that I, WILBERFORCE B. HAMMOND, of Boston, in the county of Suffolk and State of Massachusetts, have invented 5 certain new and useful Improvements in Valve-Regulating Mechanism; and I do hereby declare the following specification, taken in connection with the accompanying drawings, forming a part of the same, to be

10 a full, clear, and exact description thereof.

The invention relates to circulating or distributing systems and more especially to means for so controlling the communication between a high pressure supply and a system 15 in which the pressure is normally below the pressure in the supply that the communication between the system and supply will remain closed so long as the system pressure does not vary beyond a certain predetermined point but will open and remain open whenever the system pressure passes this point.

In practising the invention I provide a valve between the supply and the system, 25 and I control the opening of this valve through the movement of a fluid column which balances the pressure in the system and is operatively connected with an auxiliary valve by which the movements of the 30 supply valve are controlled. The intermediate devices between the auxiliary valve and the fluid column are so arranged and constructed that the auxiliary valve operates upon the movement of the fluid column 35 incident to the variation of the system pressure beyond a predetermined point and in operating is thrown out of operative relation with the fluid column so that the subsequent changes in the level of the fluid 40 column do not affect the valve. The communication between the system and supply therefore remains open after it has been once opened by the change in the system pressure.

45 The invention may be used with advantage in various systems. In "dry-pipe" sprinkler systems for instance the invention may be employed for effecting the opening of the communication between the high pressure water supply and the sprinkler system in which a low air pressure is maintained. In these systems the supply valve should remain closed until the system pressure is reduced by the opening of a sprinkler head when the supply valve should open

and remain open. My valve regulating mechanism provides a reliable means for insuring this action without the objectionable features incident to the use of the differential valves which are held to their seats by 60 the action of the air pressure in the system. This mechanism admits of a very low pressure in the system or may be arranged to operate with a partial vacuum in the system, and no amount of variation in the 65 supply pressure will effect an opening or partial opening of the supply valve or effect the proper operation of the mechanism upon the variation of the system pressure beyond the predetermined point. 70

For the purpose of illustration I have shown the invention applied to a dry-pipe sprinkler system in the accompanying drawings, in which—

Figure 1 is a sectional elevation of a portion of such a system; and Fig. 2 is a detail on an enlarged scale showing an alarm arrangement. 75

In the apparatus shown the sprinkler heads are connected in the usual manner 80 with pipes A which lead from a riser B through which water is supplied to the other parts of the sprinkler system. The communication between the riser B of the sprinkler system and the water supply pipe C is controlled by a supply valve D which is normally held to its seat D' and closes said communication. The opening of the valve 85 D depends upon the operation of an auxiliary valve E which in turn is controlled by 90 the air pressure in the system.

Any suitable construction and arrangement of supply and auxiliary valves may be employed in which the opening of the supply valve takes place upon the operation of 95 the auxiliary valve. The valve which I have shown and which I prefer to use is of the type known as the "Foster valve" and shown in patent #548,977, October 29, 1895. This valve is held to its seat by the pressure 100 of the water in the supply pipe and chamber D² such pressure being admitted to said chamber by a flow or leakage past or around the upper end or stem of the valve D, and variations in the pressure in the supply pipe 105 do not tend to open the valve or cause leakage.

When the auxiliary valve E is operated to open the discharge passage E' from the chamber D² the valve D opens and remains 110

open so long as the passage remains open and the supply pressure is maintained. When the auxiliary valve E is opened the pressure in the chamber D² is thereby reduced and a flow of water takes places past and around the valve D, which flow, in connection with the reduction of pressure in the chamber D², serves to carry the valve D upward and thus to open said valve. The opening of the valve E and consequently the opening of the valve D is effected through the movement of a fluid column which balances the pressure in the system. This fluid column is contained in a tube F the lower end of which communicates with a larger tube G. The tube G opens into a casing or chamber H which is connected with the system through a pipe I so that the fluid in the tube or chamber G is subjected to the system pressure. This pressure will be balanced by the column of fluid in the tube F which will extend above the level of the fluid in the tube G a distance depending on the pressure in the system. By varying the amount of fluid in the tubes the fluid may be made to stand at any desired levels in the tubes with a given pressure in the system.

The devices intermediate the fluid column and the valve E consist of a bar J and a lever K to which said bar is connected. The lever is provided with an arm K' arranged to engage a flange E² on the stem of the valve E. So long as the fluid stands at the level L indicated or below said level, the weight of the bar acts through the lever K to hold the valve E to its seat and the communication between the system and the supply therefore remains closed. When the pressure in the system falls owing to the opening of a sprinkler head the fluid in the tube G will rise until it floats the bar J, thus lifting the lever K and permitting the opening of the auxiliary valve E and consequently the opening of the supply valve D.

As the valve E opens the flange E² passes beyond the arm K' so that the lever has no effect on the valve when the fluid in chamber G is depressed by the pressure of the water admitted to the system. The communication between the supply and system remains open therefore after it has been once opened by the reduction of the system pressure.

When the apparatus is to be reset the valve E is returned to its seat by a lever M, one end of which is arranged to engage the flange E². The front of the flange and back of the arm K' are so shaped that the flange may be forced past the arm in closing the valve. The water may be drawn from the chamber in resetting the apparatus through a cock N.

While in the apparatus shown the lifting of the float bar by the rise of the fluid oper-

ates the auxiliary valve it will be understood that the connections may be so arranged that the valve is held to its seat by the upward pressure of the fluid column on the float and is caused to open when the fluid column falls and allows the float bar to descend. Such arrangement enables the use of a partial vacuum in the system, the fluid in chamber G standing at a higher level than the fluid in tube F until a sprinkler head opens when the pressure in the system rises, thus depressing the fluid in chamber G.

In order to avoid the necessity of employing a fluid column of inconvenient height it is preferred to employ for the controlling column a fluid of greater specific gravity than the fluid under pressure in the system. Thus when the fluid in the system is water, it is preferred to employ mercury as the fluid for the controlling column, while if the fluid in the system be air, then water may be conveniently employed for the controlling column.

It is desirable in connection with a dry-pipe sprinkler system to employ an alarm which will be sounded when the valve opens or when the pressure in the system is reduced, and in Fig. 2 there is shown a simple and efficient arrangement for sounding such an alarm. The upper end of the tube F is provided with a cup or support F' which is preferably detachably secured to said tube. Said cup is provided on its interior with brackets f f to which are secured the terminals f' f' of an electric circuit, said terminals being preferably angularly arranged with relation to each other as shown. The wires f² f² connect with the terminals f' f', and it will be understood that said terminals constitute part of an electric circuit including a battery and a bell or other alarm device. A bar or float F², adapted to float in the fluid contained in the tube F, is provided at its upper end with a contact device f³ preferably in the form of an inverted cone as shown.

So long as the fluid column stands at its normal height in the tube F the contact device f³ will be held above and out of contact with the terminals f' f', as shown in Fig. 2. When the pressure in the system is reduced so as to permit the fluid column to rise in the chamber G, the corresponding falling of the fluid column in the tube F will permit the float F² to fall and so as to bring the contact device f³ into contact with the terminals f' f' and thereby close the electric circuit and sound the alarm.

With the cup f' made detachable, said cup together with the alarm attachments, including the float F², may be readily removed, said float being lifted by the engagement of the angularly arranged terminals with the contact piece f³.

What I claim as my invention and desire to secure by Letters Patent is:

1. The combination, with a system and a valve for regulating the supply thereto and held closed by the pressure in the supply, of a fluid column balancing the pressure in the system, and devices embodying a float actuated by a variation in said column for causing the permanent opening of said valve. 5
- 10 2. The combination, with a supply valve held to its seat by the pressure in the supply, of an auxiliary valve for controlling the opening of said supply valve, a fluid column balancing the pressure in the system, and devices intermediate the fluid column and auxiliary valve for causing the permanent opening of the valve. 15
- 15 3. The combination, with a supply valve, of an auxiliary valve for controlling the opening of said supply valve, a fluid column balancing the pressure in the system, and connections between the fluid column and auxiliary valve adapted to be thrown out of operative relation on the opening of the valve. 20
- 20 4. The combination, with a supply valve, of a fluid chamber connected with the system, a fluid column balancing the pressure in the fluid chamber, a float in said chamber, and devices in said chamber between the float and valve for permanently opening the valve by the movement of the float. 25
- 25 5. The combination, with a supply valve held to its seat by the pressure in the supply, of an auxiliary valve controlling the opening of the supply valve, a fluid chamber connected with the system, a fluid column balancing the pressure in the chamber, a float in the chamber, and connections between the float and auxiliary valve adapted to be thrown out of operative relation on the opening of the valve. 30
- 30 6. The combination, with a sprinkler system having a pressure therein less than the supply pressure, of a valve for regulating the supply to said system and held closed 35
- 35 by the pressure in the supply, a fluid column balancing the pressure in the system, and means controlled by a variation in said column for effecting a permanent opening of said valve. 40
- 40 7. The combination, with a supply valve, of an auxiliary valve for controlling the opening of said supply valve, a fluid column balancing the pressure in the system, a float operated by said fluid column, and connections between said float and said auxiliary valve adapted to be thrown out of operative relation on the opening of the supply valve. 45
- 45 8. The combination, with a supply valve, of an auxiliary valve for controlling the opening of said supply valve, a fluid column balancing the pressure in the system, a float operated by said fluid column, connections between said float and said auxiliary valve adapted to be thrown out of operative relation on the opening of the supply valve, and means for resetting said auxiliary valve. 50
- 50 9. The combination, with a supply valve, of an auxiliary valve for controlling the opening of said supply valve, a fluid column balancing the pressure in the system, a float operated by said fluid column, connections between said float and said auxiliary valve adapted to be thrown out of operative relation on the opening of the supply valve, and hand-operated means for resetting said auxiliary valve. 55
- 55 10. The combination, with a tube adapted to contain a fluid column, of a cup or support detachably secured to said tube, terminals of an electric circuit carried by said support, and a float provided with a contact device adapted to engage said terminals when the support is removed from said tube, whereby said float will be removed with said support. 60
